MULTIPLE MAGAZINE ADJUSTING MEANS

Richard Henry Scott, Hale, and Arthur Staniland
 Hayward, Altrincham, England, assignors to
 Linotype and Machinery Limited, London, Eng-
 land, a British company

Application June 19, 1948, Serial No. 33,976
 In Great Britain July 23, 1947

17 Claims. (Cl. 199—45)

1

This invention relates to typographical composing machines such as those known commercially under the registered trade-mark "Linotype," and more particularly to machines employing a plurality or bank of magazines mounted in a frame which is adjustable to bring one or more of the magazines into operative relationship with assembling and distributing mechanisms. The object of the invention is to provide improved mechanism for effecting the adjustment of the magazines in operative position.

According to the present invention, a typographical composing machine having a plurality of adjustable magazines which are locked in position, is provided with an operating device which is engaged with or disengaged from a member which is connected to mechanism for transmitting to the magazines a raising and lowering movement received from the operating device when engaged with the member, while means for unlocking the magazines to permit free movement thereof are actuated by the engagement of the operating device and member.

According to a further feature of the present invention, a typographical composing machine having a plurality of adjustable main magazines which are locked in position and a plurality of adjustable auxiliary magazines which are locked in position is provided with an operating device which is selectively engaged with or disengaged from two members, the first of which members is connected to mechanism for transmitting to the main magazines a raising and lowering movement received from the operating device when engaged with the first member and the second of which members is connected to mechanism for transmitting to the auxiliary magazines a raising and lowering movement received from the operating device when engaged with said second member, while means for unlocking the main magazines to permit free movement thereof are actuated by the engagement of the operating device and first member or means for unlocking the auxiliary magazines to permit free movement thereof are actuated by the engagement of the operating device and second member.

The invention will now be described in greater detail with reference to the accompanying drawings which illustrate one constructional form which it may assume. In the said drawings:

Figure 1 is a side elevational view of a portion of a typographical composing machine equipped with hand lever control mechanism according to the present invention;

Figure 2 is an enlarged side elevational view of

2

the hand lever control mechanism with one slotted disc and the guard plate shown in Figure 1 removed;

Figure 3 is an enlarged plan view of the hand lever control mechanism with the guard plate removed, and

Figure 4 is a view similar to Figure 3, but showing the hand lever engaged with a slotted disc.

Referring to Figure 1 of the drawings, circulating matrices for use in the machine are stored in four magazines 1 carried by base frames 2 which are mounted in a bracket or shift frame 3 to form an adjustable inclined magazine column. Operation of a hand lever 4, through mechanism 10 which is later described, effects adjustment of the shift frame 3 relatively to the machine frame 5 to bring a selected magazine 1 (containing the desired fount of matrices) into operative relationship with distributing mechanism (not shown) at the upper end of the magazine column, and with assembling mechanism (not shown) at the lower end thereof. The magazine column is guided during adjustment by means of ball bearings 6 mounted on the frames 2 and 3 so as to ride on tracks 7 forming part of the machine frame 5.

The shift frame 3 has rigidly secured thereto a downward extension 8 having a foot 8^a to which is connected one end 9^a of a chain 9. The other end 9^b of the chain 9 is fastened to a pulley 10 which is freely mounted on a stationary shaft 11, such shaft being carried by bearings 12 in brackets 13 attached to a cross beam forming part of the machine frame 5. The pulley 10 is formed with a hub 14 which is fixed to a larger pulley 15 also freely mounted on the shaft 11. To the larger pulley 15 is fastened one end 16^a of a chain 16 which is passed around the pulley and over a jockey pulley 17. The other end 16^b of the chain 16 is fastened to a counter-balancing weight comprising a carrier bar 18 on which a number of removable weights 19 are supported.

The arrangement is, therefore, such that rotation of the pulleys 10 and 15 in a clockwise direction, as viewed in Figure 1, causes the chain 16 to be wound around the pulley 15, so raising the weights 19, and the chain 9 to be unwound from the pulley 10, so lowering the column of magazines 1. Similarly, rotation of the pulleys 10 and 15 in an anti-clockwise direction unwinds the chain 16 from around the pulley 15, so lowering the weights 19, and causes the chain 9 to be wound around the pulley 10, so raising the column of magazines 1.

55 A spur gear wheel 20 is formed integrally with

3

the hub 14 and meshes with a spur gear wheel 21 on a shaft 22 carried by bearings in an adjustable arm 23. To the shaft 22 is also secured a chain wheel 24 which is connected by means of an endless chain 25 to a chain wheel 26 secured to a shaft 27 carried by bearings in the machine frame. To the shaft 27 is also secured a chain wheel 28 which is connected by means of an endless chain 29 to a chain wheel 30 (see Figure 3) secured to a sleeve 31 on a shaft 32 carried by bearings in the machine frame.

A slotted disc 33 provided with slots 34 (see Figures 2 and 3) is secured to the sleeve 31. Also loosely mounted on the shaft 32 adjacent the sleeve 31 is a sleeve 35 carrying studs 36 on which the hand lever 4 is pivotally mounted. Adjacent the sleeve 35 and loosely mounted on the shaft 32 is a second sleeve 31^a to which is secured a second slotted disc 33^a provided with slots 34^a. A second chain wheel 30^a is secured to the sleeve 31^a and is connected by chain and wheel mechanism (similar to that already described for connecting the chain wheel 30 to the chain wheel 24) to gear and pulley mechanism (similar to that already described for raising and lowering the column of magazines 1) for raising and lowering a second column of auxiliary magazines (not shown).

The hand lever 4 is provided on one side with a projection 37 (see Figures 3 and 4) which can be brought by pivotal movement of the hand lever 4 into engagement with a slot 34 in the disc 33. As the sleeve 35 is loosely mounted on the shaft 32, the hand lever 4 can, after the engagement of the projection 37 with a slot 34, be moved upwardly as indicated by the broken line in Figure 1, to turn the disc 33 and consequently rotate (through the chain and wheel connections described) the pulleys 10 and 15 and raise the column of magazines 1. The hand lever 4 is moved sideways to disengage the projection 37 from the slot 34 and is then moved downwardly to the position indicated in full lines in Figure 1. If a further raising movement of the column of magazines 1 is required, the hand lever 4 is moved to engage the projection 37 with a succeeding slot 34 and is again moved upwardly to rotate the disc 33. If it is desired to lower the column of magazines, the hand lever 4 is moved downwardly while the projection 37 is in engagement with a slot 34, to rotate the disc 33 in an anti-clockwise direction. When the lowermost position of the hand lever indicated in Figure 1 is reached, the projection 37 is disengaged from the slot 34, and if desired, it is engaged with a succeeding slot 34. Stops 38 on a guard 39 limit the upward and downward movement of the hand lever 4.

On its other side the hand lever 4 is provided with a projection 37^a which can be brought into engagement with the slots 34^a in order to rotate the disc 33^a (in a manner similar to that in which the disc 33 is rotated) and so raise or lower the auxiliary column of magazines.

Pivoted mounted at 40 on one side of the hand lever 4 (see Figures 3 and 4) is an arm 41 provided with a roller 42 which, on sideways movement of the hand lever 4, is brought into engagement with a flange 43 on the disc 33 to turn the arm 41 inwardly towards the hand lever 4, as indicated by dot-and-dash lines in Figure 4. The arm 41 is connected through the pivot 40 to an arm 44 (see Figure 2) provided with a post 45 to which one end of a spring 46 is secured. The other end of the spring 46 is secured to a post 47 on the hand lever 4.

4

On the other side of the hand lever 4 there is pivotally mounted at 40^a an arm 41^a (see Figures 3 and 4) provided with a roller 42^a which, on movement of the hand lever 4 from the position shown in Figure 3 to the position shown in Figure 4, is brought into engagement with a flange 43^a on the disc 33^a to turn the arm 41^a inwardly towards the hand lever 4, as shown in Figure 4. The arm 41^a is connected through the pivot 40^a to an arm 44^a provided with a post 45^a (see also Figure 2) to which one end of a spring 46^a is secured. The other end of the spring 46^a is secured to a post 47^a on the hand lever 4.

Thus, when the hand lever 4 is moved sideways to bring the projection 37 into engagement with a slot 34 in the disc 33 as shown in Figure 4, the arm 41 is turned against the action of spring 46 and when the hand lever 4 is released, the spring 46 returns it to the position shown in Figure 3 with the arm 44 abutting against a stop pin 48. Similarly, the arm 41 is turned against the action of spring 46 when the hand lever 4 is moved to the position shown by dot-and-dash lines in Figure 4, and when the hand lever 4 is released, the spring 46 returns it to the position shown in Figure 3 with the arm 44 abutting against a stop pin 48 (Figure 2).

As more clearly seen in Figure 2, the arm 44 at its outer end adjacent the post 45 is provided with a second post 49 to which is secured one end of a flexible cable 50, such as a "Bowden" wire, which passes through the post 47 on the hand lever 4. The flexible cable 50 (see Figure 1) is connected at its other end to a lever 51 which is pivoted at 52 to the machine frame 5. The lever 51 has secured thereto a stud 53 bearing against a locking arm 54 which engages locating studs 55 on the magazine base frames 2. The sideways movement of the hand lever 4 to the position shown by dot-and-dash lines in Figure 4, and consequent turning of the arm 44 thus exerts a forward pull on the cable 50 and effects an unlocking movement of the locking arm 54 preparatory to the adjustment of the column of magazines 1. Release of the hand lever 4 allows the spring 46 to return the parts to the position in which the magazine column is locked by the locking arm 54.

The arm 44^a at its outer end adjacent the post 45^a is provided with a second post 49^a to which is secured one end of a flexible cable 50^a which passes through the post 47^a. The other end of the flexible cable 50^a is connected to mechanism (not shown) for unlocking the auxiliary column of magazines when the hand lever 4 is moved to the position shown in Figure 4 preparatory to the adjustment of the auxiliary column of magazines. Release of the hand lever 4 allows the spring 46^a to return the parts to the position in which the auxiliary column of magazines is locked against movement.

Having described our invention, we declare that what we claim and desire to secure by Letters Patent is:

1. In or for a typographical composing machine of the shiftable magazine variety, magazine raising and lowering mechanism comprising, in combination, a rotatable member for imparting a raising or lowering movement to the magazine column, a hand lever movable upwardly and downwardly to operate said rotatable member, a rotatable support for the hand lever to permit of such upward and downward movements, said support being freely rotatable with respect to the rotatable member and mounted to turn about the

5

same axis, a pivotal connection between the rotatable support and the hand lever to permit the hand lever to be moved laterally with respect to the rotatable member, and means for coupling the hand lever directly to the rotatable member, said coupling means comprising elements which are engaged and disengaged by opposite lateral movements of the hand lever, respectively.

2. The combination according to claim 1, including means for limiting the extent of the upward and downward movements of the hand lever.

3. The combination according to claim 2, wherein the extent of the upward or downward movement of the hand lever, as controlled by the limiting means, is sufficient to make a shift from one magazine to the next adjacent one in the column.

4. The combination according to claim 1, wherein the rotatable member is provided with coupling elements at different circumferential points.

5. The combination according to claim 4, wherein the spacing of the different circumferential coupling elements on the rotatable member corresponds to a magazine raising or lowering movement for a shift from one magazine to the next adjacent magazine into the column.

6. The combination according to claim 1, wherein the rotatable member is formed with a plurality of radially disposed slots, one for each magazine in the column, and the hand lever is formed with a radially disposed projection engageable in one or another of said slots.

7. The combination according to claim 1, including a spring connected to the hand lever and acting constantly to maintain it in a neutral position, uncoupled from the rotatable member.

8. The combination according to claim 1, including means actuated by the pivotal movement of the hand lever into couple relation with the rotatable member to unlock the magazine column for a raising or lowering movement.

9. The combination according to claim 8, including a spring connected to the hand lever and acting constantly to maintain it in a neutral position, uncoupled from the rotatable member and with the magazine column locked against movement.

10. In or for a typographical composing machine of the shiftable magazine variety, magazine raising and lowering mechanism comprising, in combination, a pair of rotatable members mounted to rotate about a common axis, one for imparting a raising or lowering movement to one magazine column, and the other for imparting a raising or lowering movement to a second magazine column, a hand lever located between the two rotatable members and movable upwardly and downwardly to operate either selected one thereof, a rotatable support for the hand lever to permit of such upward and downward movements, said support being freely rotatable with respect to the rotatable members and mounted to turn about the same axis, a pivotal connection between the rotatable support and the hand lever to permit the hand lever to be moved laterally with respect to either selected one of the rotatable members, and means for coupling the hand lever directly to either selected rotatable member, said means comprising elements which are engaged and disengaged by opposite lateral movements of the hand lever with respect to said selected member, respectively.

6

cluding a spring connected to the hand lever and acting constantly to maintain it in a neutral position, uncoupled from both of said rotatable members.

5 12. The combination according to claim 10, including means actuated by the pivotal movement of the hand lever into coupled relation with one of said rotatable members to unlock the corresponding magazine column for a raising or
10 lowering movement, and means actuated by the pivotal movement of the hand lever into coupled relation with the other of said rotatable members to unlock the corresponding magazine column for a raising or lowering movement.

15 13. The combination according to claim 12, including a spring connected to the hand lever and acting constantly to maintain it in a neutral position, uncoupled from both of said rotatable members and with both magazine columns locked
20 against movement.

14. In or for a typographical composing machine of the shifttable magazine variety, magazine raising and lowering mechanism comprising a hand lever, a sleeve on which said hand lever is pivotally mounted, a shaft on which said sleeve is loosely mounted for rotary movement of the hand lever in opposite directions, a slotted disc mounted to turn about the axis of said shaft and provided with slots arranged to be engaged by the hand lever on pivotal movement thereof, and mechanism for transmitting from said slotted disc to the magazines a raising or lowering movement obtained by rotary movement of the hand lever when engaged with a slot in the slotted disc.

15. In or for a typographical composing machine adapted to be equipped with a plurality of shiftable main magazines and a plurality of shiftable auxiliary magazines, magazine raising and lowering mechanism comprising a hand lever, a sleeve on which said hand lever is pivotally mounted, a shaft on which said sleeve is loosely mounted for rotary movement of the hand lever in opposite directions, a slotted disc also 10 loosely mounted on said shaft and provided with slots arranged to be engaged by the hand lever on pivotal movement thereof in one direction, mechanism for transmitting from said slotted disc to the main magazines a raising or lowering 15 movement obtained by rotary movement of the hand lever when engaged with a slot in the disc, a second slotted disc likewise loosely mounted on said shaft and provided with slots arranged to be 20 engaged by the hand lever on pivotal movement thereof in the opposite direction, and mechanism for transmitting from said second slotted disc to the auxiliary magazines a raising or lowering 25 movement obtained by rotary movement of the hand lever when engaged with a slot in the second slotted disc.

16. In or for a typographical composing machine of the shiftable magazine variety, magazine raising and lowering mechanism comprising a hand lever, a sleeve on which said hand lever is pivotally mounted, a shaft on which said sleeve is loosely mounted for rotary movement of the hand lever in opposite directions, a slotted disc mounted to turn about the axis of said shaft and provided with slots arranged to be engaged by the hand lever on pivotal movement thereof, mechanism for transmitting from said slotted disc to the magazines a raising or lowering movement obtained by rotary movement of the hand lever when engaged with a slot in the disc, locking

7

mechanism for holding the shiftable magazines in position, a flexible cable connected at one end to said locking mechanism, and a lever pivoted on the hand lever and connected to the other end of said flexible cable, the said lever being adapted to be moved by contact with the slotted disc to actuate the locking mechanism and unlock the magazines as the hand lever is engaged with a slot in the slotted disc.

17. In or for a typographical composing machine adapted to be equipped with a plurality of shiftable main magazines and a plurality of shiftable auxiliary magazines, magazine raising and lowering mechanism comprising a hand lever, a sleeve on which said hand lever is pivotally mounted for rotary movement of the hand lever in opposite directions, a shaft on which said sleeve is loosely mounted, a slotted disc also loosely mounted on said shaft and provided with slots arranged to be engaged by the hand lever on pivotal movement thereof in one direction, mechanism for transmitting from said slotted disc to the main magazines a raising or lowering movement obtained by rotary movement of the hand lever when engaged with a slot in the disc, locking mechanism for holding the shiftable main magazines in position, a flexible cable connected at one end to said locking mechanism, a lever pivoted on the hand lever, and connected to the other end of said flexible cable, the said lever being adapted to be moved by contact with the

5

10

15

20

25

slotted disc to actuate the locking mechanism and unlock the main magazines as the hand lever is engaged with a slot in the slotted disc, a second slotted disc likewise loosely mounted on said shaft and provided with slots arranged to be engaged by the hand lever on pivotal movement thereof in the opposite direction, mechanism for transmitting from said second slotted disc to the auxiliary magazines a raising or lowering movement obtained by rotary movement of the hand lever when engaged with a slot in the second slotted disc, a second flexible cable connected at one end to the locking mechanism for holding the shiftable auxiliary magazines in position, a second lever pivoted on the hand lever and connected to the other end of said second flexible cable, the said second lever being adapted to be moved by contact with the second slotted disc to actuate the locking mechanism and unlock the auxiliary magazines as the hand lever is engaged with a slot in the second slotted disc.
